(57) **CLAIM**

The ornamental design for a table lamp, as shown and described.

DESCRIPTION

FIG. 1 is a front, top, and left side perspective view of a table lamp, showing my new design;

FIG. 2 is a front view of a table lamp.

FIG. 3 is a rear view of a table lamp.

FIG. 4 is a left side view of a table lamp.

FIG. 5 is a right side view of a table lamp.

FIG. 6 is a top view of a table lamp.

FIG. 7 is a bottom view of a table lamp; and,

FIG. 8 is a front, bottom, and left side perspective view thereof.

Any shading and cross-hatching are not features of the design but are utilized to illustrate the surface contours of the table lamp design in the drawings.

In the drawings, the broken lines illustrate portions of the article which form no part of the claimed design.
